C. E. WESTER
CIGARETTE DISPENSER

1,916,453

Filed March 3, 1931

UNITED STATES PATENT OFFICE

CHARLES E. WESTER, OF IRONWOOD, MICHIGAN

CIGARETTE DISPENSER

Application filed March 3, 1931. Serial No. 519,910.

This invention relates to dispensing devices and pertains particularly to a device for dispensing cylindrical articles such as cigarettes or the like.

5 The primary object of the present invention is to provide a novel cigarette cabinet which will dispense individual cigarettes into a receiver forming a part thereof.

Another object of the invention is to provide a cigarette dispenser in which the storage or magazine section thereof must be oscillated in order to uncover the outlet thereof from which a cigarette may pass by gravity into a receiver.

10 Still another object of the invention is to provide a cigarette dispenser which is designed primarily as a novelty for use in the home, although it is not to be confined to such use, which is of a neat and attractive appearance and calculated to provide an article of ornamentation as well as of utility.

15 Still another object of the invention is to provide a cigarette dispensing device having an oscillatable magazine which is moved with relation to a fixed closure member for effecting the removal of a cigarette therefrom, the closure member carrying receiving arms into which the cigarette is discharged.

20 Other objects and advantages of the invention will become apparent as the description of the same proceeds and the invention will be best understood from a consideration of the following detailed description taken

25 in connection with the accompanying drawing forming a part of the present invention with the understanding, however, that the invention is not confined to any strict conformity with the showing of the drawing but 30 may be changed or modified so long as such changes or modifications mark no material departure from the salient features of the invention as expressed in the appended claims.

35 In the drawing:—
40 Figure 1 shows the cigarette dispensing device embodying the present invention and a loading clip in position in the top thereof, showing the manner in which the device is charged with the cigarettes;

45 Figure 2 is a central longitudinal sectional

view through the dispenser showing in dotted lines the position assumed by the body thereof in the discharge of a cigarette;

50 Figure 3 is a view in rear elevation of the device;

55 Figure 4 is a sectional view taken on the line 4—4 of Figure 2.

60 Referring more particularly to the drawing wherein like numerals of reference indicate corresponding parts throughout the several views, the numeral 1 indicates the base of the cigarette dispenser, upon the center of which is mounted a triangular supporting body 2 which has the horizontally disposed base face 3, the vertical right angularly disposed rear face 4 and the forwardly and downwardly inclined top face 5 upon which the cigarette receptacle or magazine of the present device normally rests.

65 The cigarettes are contained in the flat casting or magazine receptacle 6. This receptacle may be of the square design shown, or it may be in the form of an elongated rectangle, if desired. From the under face of the receptacle there extends a pair of spaced 70 ears 7 between which is located the supporting base 2 and to which the ears are connected by the pivot pin 8, which extends transversely through the base, as shown in Figures 2 and 3. This pin 8 is, as shown, located adjacent 75 the top portion of the rear of the base so that the receptacle may be oscillated over the top of the rear face thereof, as illustrated in Figure 2.

80 The upper and lower ends of the receptacle 85 6 are open as indicated at 9 and 10, respectively, and the upper end is normally covered or closed by the lid 11. This lid has formed integral therewith, at one longitudinal edge, the right angularly extending wings 12 90 which have spaced inner edges from which there project the right angularly directed hinge ears 13. These ears 13 are pivotally mounted upon the pin 8, like the ears 7 which support the cigarette receptacle.

95 The ears 13 extend forwardly of the wings 12 to which they are attached and the upper edges 14 thereof form an acute angle with the under face of the receptacle when the lid is in closed position and when the lid is opened 100

these edges 14 swing upwardly into contact with the under side of the receptacle and thus limit the swinging movement of the lid.

The opposite longitudinal edge of the lid 5 from the edge to which the wings 12 are attached has formed intermediate its ends the catch 15 which springs over the forwardly pressed portion 16 of the top edge of the forward face of the receptacle, as shown in 10 Figure 2, to hold the lid in closed position.

Secured to the rear face 4 of the base 2 is a movement limiting plate 17 for the receptacle 6. As shown, this plate has a longitudinal slot 18 therein through which there 15 extends into the base the screw 19. By loosening this screw the stop plate 17 may be raised or lowered so that the top end, which projects above the top of the base 2 will be engaged by the receptacle when the 20 same is oscillated, and will thus act to limit the oscillatory movement thereof.

At the forward end of the receptacle 6 there is positioned a fixed cover plate 20 which is disposed at the proper angle to lie 25 across the open end 10 of the receptacle when the same is at rest upon the base 2. This plate 20 may be secured in any suitable manner, as for example, it may have formed integral with the lower edge thereof the plate 21 which may be secured to the base 1 between 30 the same and the body 2.

The upper edge of the cover plate 20 has formed integral therewith a pair or more of 35 relatively broad forwardly and upwardly curving arms 22 onto which a cigarette may roll when the receptacle is oscillated to raise the open lower end 10 thereof above the cover plate 20, as illustrated in dotted lines in Figure 2.

40 From the foregoing description it will be readily seen that by placing the fingers against the face of the receptacle 6 adjacent the upper end thereof and pressing downwardly thereon, the lower end will be raised 45 through the oscillation of the receptacle on the pivot ears 7, until stopped by the plate 17. If the plate 17 is properly set it will stop the oscillation of the receptacle just as the forward end thereof becomes completely 50 uncovered so that a cigarette will be permitted to roll out upon the receiving arms 22.

In charging the receptacle 6 there is provided a carton which is indicated generally by the numeral 23, in which the cigarettes 55 may be packed by the manufacturer. The lower end of this carton is open and the forward face thereof is also open, as shown, so that by inserting the carton into the upper end of the receptacle and placing one finger 60 into the open face thereof while pulling the carton out of the receptacle, the cigarettes therein may be effectively transferred to the receptacle. This carton forms the subject-

matter of a separate application for patent.

Having thus described my invention, what I claim is:—

1. A cigarette dispensing device comprising a flat rectangular receptacle, means for normally supporting the receptacle at an inclination, from the horizontal, the lower edge of the receptacle having an opening to permit a cigarette to roll therefrom by gravity, pivotal supporting means beneath the receptacle adjacent the upper edge thereof, a plate closure member fixedly arranged to cover the open lower end of the receptacle when the same is in normally inclined position, and means adapted to be secured in an adjusted position beneath the receptacle adjacent the upper edge thereof, for regulating the degree of oscillation thereof. 70 75

2. A cigarette dispensing device comprising a flat rectangular receptacle, a substantially triangular supporting base for the receptacle having an inclined surface upon which the receptacle rests, ear members secured to the under side of the receptacle and having said base disposed therebetween, pivot 80 85 means carried by the base for engagement by said ears, a lid covering the upper edge of the receptacle and having a pair of right angularly disposed wings extending beneath the receptacle, said wings being in spaced 90 95 relation and having the opposed edges thereof provided with right angularly extending ears having said base disposed therebetween, said pivot means being engaged by said last ears, said wing carried ears being extended 100 beneath the receptacle to form stops adapted to engage the receptacle to limit the movement of the lid, and means for uncovering the other edge of the receptacle and for receiving a cigarette therefrom when the receptacle is oscillated. 105

3. A cigarette dispensing device comprising a flat rectangular receptacle, a substantially triangular supporting base therefor having an inclined surface upon which the receptacle rests, pivot ears projecting from the under face of the receptacle and having said base disposed therebetween, means for pivotally securing the ears to the base, said receptacle having the upper and lower edges, open, a cover removably positioned over the open upper edge of the receptacle, a fixed closure secured at an inclination across the open lower edge of the receptacle, the receptacle being oscillatable away from the fixed closure to uncover the lower edge thereof, and a flat member disposed vertically upon the said base beneath the receptacle and adjustable vertically to regulate the oscillatory movement thereof. 110 115 120 125

In testimony whereof I hereunto affix my signature.

CHARLES E. WESTER.
